Specification of Letters Patent.

Patented Jan. 30, 1917.

Application filed February 8, 1915. Serial No. 6,753.

To all whom it may concern:

Be it known that I, HUBERT EDWIN HOOD, a citizen of Canada, residing at Buffalo, in the county of Erie and State of New York, have invented new and useful Improvements in Boxes, of which the following is a specification.

This invention relates to a box which is more particularly designed for packing shoe 10 polishing paste although the same may also be used for packing other materials.

It is essential in boxes used for packing shoe blacking that a tight joint is maintained between the cover and the body there- 15 of so that air will be excluded from its contents and the latter prevented from drying out. When, however, a tight joint is produced between the cover and body it is usually very difficult to open the box by 20 means of the hands only.

It is therefore the purpose of this invention to provide a box of this character with an opening device which is comparatively simple and compact in construction, which 25 requires no more metal in its manufacture than that used in the manufacture of the boxes heretofore in use, which permits of obtaining a powerful leverage so as to enable the box to be easily opened, and which 30 is so constructed that the same can be very easily and readily manipulated by any one having no previous experience with the same.

In the accompanying drawings: Figure 1 35 is a front elevation of a box equipped with my improved opening device and showing the box in its closed position. Fig. 2 is a top plan view thereof. Fig. 3 is a front elevation of the box, showing the opening device partly in section and the cover lifted 40 part way from the body. Fig. 4 is a horizontal section taken in line 4—4, Fig. 1 looking downwardly. Figs. 5 and 6 are fragmentary vertical transverse sections 45 taken in the correspondingly numbered lines in Figs. 1 and 3, respectively. Fig. 7 is a fragmentary horizontal section taken in line 7—7, Fig. 1, looking upwardly.

Similar characters of reference indicate 50 corresponding parts throughout the several views.

Although my improvements are applicable to boxes which may be used for various purposes and which may vary in general design, 55 that shown in the drawings is more particu-

larly intended for packing shoe blacking paste and comprises a lower circular body which is provided with a bottom 1 and an upwardly projecting annular flange 2 at the edge of the bottom, and a circular cover 60 having a top 3 and a downwardly projecting annular flange 4 which fits over the flange of the body. In its closed position the lower edge of the cover flange is arranged close to or actually engages with an 65 annular outwardly projecting bead or shoulder 5 formed on the flange of the body. These two parts of the box are preferably constructed of tin or other suitable material in any usual and well known manner. My 70 improved opening device which is applied to this box to permit of easily opening the same may be variously organized to suit the particular box on which the same is used but when applied to a round box, as shown 75 in the drawings, the same is preferably constructed as follows: On the outer side of one part of the cover flange is arranged a supporting bracket which in its preferred form comprises a horizontal web 6 projecting outwardly from the lower edge of the cover flange, an upright wall 7 projecting upwardly from the outer edge of the web and substantially parallel with the cover flange, 80 and a stop lip 8 projecting horizontally inward, or substantially so, from the upper edge of the wall toward the cover flange and preferably into engagement with the same, 85 as shown in Figs. 2, 5 and 6. This bracket is preferably constructed integrally with the 90 cover from the same sheet of metal, it being possible to do this without using any more metal than has heretofore been required to produce an ordinary cover inasmuch as this bracket can be stamped out of 95 the metal which has heretofore been cut away between adjacent cover blanks and wasted.

The web of the bracket is provided with 100 an opening or slot 9 which preferably is of the same width as the distance between the wall and the cover flange but terminates at its opposite ends short of the ends of the web so as to retain a connection between the wall and the lower edge of the cover flange, as best shown in Figs. 4 and 7. A lever is provided for lifting the cover from the body with ease and certainty, this lever being 105 preferably constructed from a piece of metal wire in the form of the letter U so 110

as to produce an inner bearing arm 10 which is comparatively short, an outer operating arm 11 which is adapted to be grasped by the fingers for manipulating the lever and a bight or cross piece 12 connecting the corresponding inner ends of these lever arms. The bight of this lever is arranged in an opening 13 formed in the wall of the bracket adjacent to the upper end thereof and about vertically in line with one end of the slot 9 whereby a pivotal connection is produced between this lever and the bracket. When thus assembled the short inner or bearing arm of the lever is arranged between the inner side of the wall of the bracket and the outer side of the cover flange while the outer operating arm of the same is arranged outside of the bracket wall, as shown in Figs. 4-7.

20 In the normal closed position of the box the lever projects downwardly from its pivot at an angle to the shoulder or bead of the body, as shown, in Fig. 1 in which position the inner arm of the lever may rest loosely against the shoulder or bead of the body. When it is desired to open the box it is only necessary to turn the lever in a direction which will cause its inner arm to turn downwardly into an upright position

25 whereby this inner arm by passing downwardly through the slot of the bracket and sweeping over a part of the body bead will cause the cover to be pried up or lifted from the body a sufficient extent to loosen the same, as shown in Fig. 3, so that the complete removal of the cover may be effected subsequently with comparative ease by sole use of the fingers. By arranging the pivot of the lever about in line with one

30 end of the slot said end serves as a stop which limits the throw or swing of the lever in the direction for opening the box and arrests this opening movement when the lever reaches a vertical position in which it has produced the maximum lifting effect which it is possible to exert upon the box by the lever. By providing the upper end of the wall with an inturned stop lip this

35 wall is not only braced and prevented from becoming displaced while handling or packing the box but this lip also serves as a stop which limits the upward movement of the

inner arm of the lifting lever and insures retaining the lever in its proper position so that an inexperienced person will have no difficulty in properly manipulating this lever for the purpose of opening the box. The lower end of the inner bearing arm of the lever is preferably flattened or broadened somewhat, as shown in Figs. 4-7, so as to increase the extent of its contact with the body bead or shoulder and thereby insure proper lifting of the cover from the body. This opening device as a whole is very simple in construction, the same can be produced without any material increase in cost, it permits of packing boxes for shipment as closely as has been possible heretofore, and persons without any previous experience are capable of opening the box readily and quickly. Furthermore, this construction of opening device in nowise affects the air tight joint between the cover and the body, so that there is no liability of the contents of the box drying out by the entrance of air.

I claim as my invention:

A box comprising a body having a flange provided with an outwardly projecting annular bead or shoulder, a cover having a flange fitting over the flange of the body and provided on its outer side with a bracket having a web projecting laterally from the lower edge of the cover flange, an upright wall projecting upwardly from the outer edge of said web and along the outer side of said cover flange, a slot in said web and a stop lip projecting inwardly from the upper edge of said wall toward the cover flange, and a lever pivoted on said wall and having an inner arm arranged between the wall and cover flange and adapted to swing upwardly into engagement with said slot and against one end of the latter and also against said body shoulder and an outer arm arranged outside of said wall and adapted to be manipulated.

Witness my hand this 6th day of February, 1915.

HUBERT EDWIN HOOD.
